UNITED STATES PATENT OFFICE.

WILLIAM T. HANCOCK AND CHARLES E. WHITLOCK, OF RICHMOND, VA.

DESIGN FOR PLUG-TOBACCO.

Specification forming part of Design No. **11,532**, dated December 2, 1879; application filed October 24, 1879.
[Term of patent 7 years.]

To all whom it may concern:

Be it known that we, WILLIAM T. HANCOCK and CHARLES E. WHITLOCK, of Richmond, in the county of Henrico and State of Virginia, have originated a new Design for Plug-Tobacco, of which the following is a full, clear, and exact description, reference being had to the accompanying drawing, making part of this specification, and representing a perspective view of a plug of tobacco formed according to our design.

The letter A designates the plug of tobacco, which has the general form of a parallelopiped, the edges or narrower sides, B, of which are smooth, while the wider sides, C, are corrugated by furrows *d*, having a shape as if formed by pressing a series of twisted cords lying side by side partly into the surfaces of the plug.

We do not, of course, confine ourselves to a plug having more than one side corrugated, as described and shown, as, were but one side so corrugated, the plug would present the same appearance, viewed directly, as though all were so.

It will be seen that in a plug of tobacco of the design described the aesthetic appearance of the plug is greatly increased, and it presents a more pleasing effect to the eye, while it is apparent that the plug has been compactly compressed, thereby rendering it more salable.

What we claim is—

The design for a tobacco-plug, consisting in the general form of a parallelopiped, having one or more of its surfaces corrugated by indentations, having a shape as if formed by pressing a series of twisted cords lying side by side partly into the said surface or surfaces, essentially as shown in the accompanying drawing.

In testimony that we claim the foregoing we have hereunto set our hands in the presence of two witnesses.

WILLIAM T. HANCOCK.
CHARLES E. WHITLOCK.
